TORCH

Filed Oct. 18, 1926

Inventor

William H. McNutt.

By his Attorney Wm. H. Reid.

UNITED STATES PATENT OFFICE.

WILLIAM H. MCNUTT, OF NEW YORK, N. Y.

TORCH.

Application filed October 18, 1926. Serial No. 142,243.

This invention relates to a torch in the form of a tube attached to a container for the liquid to be burned.

One of the objects of the invention is to provide in a device of this character, a valve control whereby the liquid will not spill out in any position, but when inverted and the bottom pressed, the valve will rise and permit flow of the liquid into the torch body.

10 A further object of the invention is to provide such a device in which the valve will open outwardly, whereby upon generation of considerable pressure in the container, the valve will raise under pressure and permit escape of the gas generated, until the pressure is relieved.

15 A further object of the invention is to provide in connection with a suitable removable container, a perforated torch tube that is carried by the container, which tube contains porous material and which will have a controlled valve, that can be operated by the user to permit the desired quantity of the liquid to pass to the interior of the tube.

20 Another object of the invention is to provide a container in somewhat of the form of an oil can or a squirt can with a deflected bottom wall, so that by inverting the device, a desired quantity of the liquid can flow out by merely pressing inwardly on the bottom.

25 A further object of the invention is to provide a torch device in which a perforated tube will hold a quantity of fuel in a porous mass in the tube, to be ignited, and to provide adjustable means for feeding a current of air to the flame that will provide a kind of Bunsen burner effect, so that a blue flame or a green flame will be produced, and the efficiency much increased.

30 In the accompanying drawing showing one embodiment of my invention,

Fig. 1 is a side elevation partly broken away.

35 Fig. 2 is a vertical section through the same.

Fig. 3 is a vertical section enlarged adjacent the valve.

Fig. 4 shows a modification.

40 As shown in the drawing, I provide a container in somewhat the form of a squirt can, having a conical body 2 and a dished bottom 3 that can be pressed inwardly, and will return to its outer convex position as shown. The body has a closure member 4, screw

55 threaded to screw into the screw threaded extension 5 of the body 2. This closure member is shown provided with an extension tube or spout 6, that is usually conical, and forms the outlet for the container. This outlet is shown as controlled by a suitable valve pressed inwardly by a spring, and which valve member is brought down for engagement with the bottom 3, so that when the bottom is pressed inwardly or upwardly the valve will open for discharge of the contents when the container is inverted. In the form shown I provide a valve stem 7, that carries a ball 8 at the upper end. A sleeve 9 is placed on the stem, and then the stem and ball with the sleeve are inserted in the outlet spout 6 as shown. The sleeve forms a tight fit therein, and is secured by a suitable means, such as solder. It will be seen from Fig. 4 that the ball valve engages the inner edge of the sleeve 9. The stem 7 is shown as carrying a spiral spring 10, that presses at its upper end against the closure 4, while the lower end is secured to the stem by suitable means, such as a nut 11 and washer 12.

50 If desired a plug of solder 13 may be arranged around the stem end to form a rounded plug for engagement with the bottom wall 3 as shown. Since the closure is removable these parts can be readily assembled, and the stem is so designed that when

55 the closure is inserted the lower end of the stem will engage the outwardly deflected bottom 3, while the spring will hold the valve tightly seated, and prevent escape of the contents in any position of the container. Obviously, when the container is inverted and the bottom pressed inwardly in the usual manner of operating a squirt can, the ball

60 valve 8 will be lifted from the seat, and the contents will flow outwardly as long as the valve is raised; but as soon as the valve is released the spring will again seat the valve, and prevent escape of the fluid, or any gas that may be in the container. This is of great advantage where a liquid is employed

65 that is quickly evaporated, but it will be seen that this furnishes a safety valve, whereby upon a high pressure in the container, the valve will thereby be raised, and permit the slow escape of the gas through the outlet spout, until the pressure is relieved, when the valve will again seat.

70 Another portion of my invention is a torch

or torch tube, that is attached to a container, that will form a base therefor, and which container is provided with a valve normally closed, but on operation of a certain part 5 of the container, its contents will be caused to flow by gravity into the interior of the torch to saturate a porous wall of the same, so that only the desired quantity for immediate use will be admitted to the torch.

10 As shown I provide a torch tube 14, that has its upper end portion 15 perforated, and the end closed by a wall 16 having a flange 17. A sleeve tube 18 slides on the tube 14, from the position shown in Fig. 2, where 15 this sleeve entirely closes the perforated portion 15, but when moved down to its lower position indicated in Fig. 1, the perforated portion 15 of the tube is exposed. The tube 14 is shown as suitably mounted on the closure 4 of the container 2, and is secured thereon, by solder. The outlet or spout 6 that projects up from the closure 4, extends into the torch tube 14, and terminates at about the middle portion. The torch tube 20 contains suitable porous material, such as asbestos 19, extending around the spout tube 6 from its lower portion, and which fills the tube 14 around and above the spout 6. It will thus be seen that a porous mass is provided between the spout 6 and the tube 14. The sleeve 18 may have a tight fit on the tube 14 as shown in Fig. 4, but preferably is made slightly larger than the inner tube so that a passage for air is provided in all 25 positions of the sleeve except in the upper position where the perforations are closed. Means are preferably provided to retain the sleeve in all positions, and as shown two friction clips 21 and 22 are secured to the 30 sleeve, as by rivets, that will press against the tube 14 and hold the sleeve in all positions. This sleeve as stated will serve to expose all of the perforations, or any desired portion of them, by sliding it down, but at 35 the same time a free passage for air is provided through the sleeve between it and the inner tube. When the torch is ignited at the 40 perforations exposed, the flame in burning will draw air up between the sleeve and tube, and will pass into the interior of the flame, and act precisely on the Bunsen burner principle, as has been found by repeated experiment. It has been further discovered that 45 in a torch and torch tube of this nature a smaller relative portion of the torch tube is needed to give the required flame, because of this greater intensity. It has been further discovered that a much cheaper fuel can be employed; where alcohol or its equivalent 50 was used, a mixture of a hydro-carbon costing much less can be used, and a much better flame produced.

It will be understood that the container 2 forms a suitable base for the device, so that 55 it can be placed on a floor or table, or any

suitable place, while the old form of torch tube had to be returned to its can, or a special form of holder.

In the use of the device, the closure to which the torch is secured, is unscrewed and the container filled with the desired fuel, as gasoline, or other fluid. When the closure is returned to place the container will be effectually closed by the ball valve, and the device is now inverted and the bottom of the 70 can is depressed, that will allow the fluid to pass down through the spout into the absorbent mass inside of the torch tube, and saturate it, when the torch can be ignited, by 75 sliding the sleeve down from its upper position, the required distance to give the desired flame; or the sleeve can remain in the upper closing position until it is desired to use the torch any time later, as the small 80 perforated portion is not exposed and the fluid will not evaporate or spill. Only sufficient of the fluid is permitted to pass into the tube to saturate the torch tube mass, and none of the fluid will run down onto the can 85 or the hand of the user. It will be further understood that the torch can be held in any position but will not spill the fluid. When the flame becomes reduced or extinguished, the device is merely inverted and the bottom 90 pressed, when another portion of the fluid 95 will pass down into the torch tube.

In the present construction of safety torches for thawing frozen gas and water pipes, the torches are filled or charged by 100 means of absorption, by keeping the torch constantly immersed in the burning fluid, using a special safety can, in combination with the torch. The removal of the torch from the safety can usually will cause the liquid to run down to the hand and clothing 105 of the user when igniting the torch and danger of causing a fire is much greater with the separate storage can separate from the torch, than with the present form of combined torch and container. Another objection is the great waste of fuel where a storage can is exposed on removal of the torch tube, as the fuel will quickly evaporate. 110

In Fig. 4 is shown a modification in which the spout 6 is surrounded by a tube 20 of 115 perforated metal that is enclosed in the mass 19 of asbestos or other porous material. This forms a chamber around the spout and the fuel from the container will first enter this chamber and then be absorbed by the asbestos. 120

What I claim is:

1. A torch device comprising a torch tube 125 perforated for a portion of its length, a mass of refractory porous material in the tube, a sleeve slidable outside of the tube to entirely expose the perforations in one position, and to slide to enclose more or less of the perforated portion, and restrict the flame, said sleeve being slightly larger than the tube to 130

provide a free endwise passage for the air through the sleeve between the tube and sleeve, in all intermediate positions to form a Bunsen burner flame, and means to hold the sleeve in adjusted positions.

2. A torch device comprising a torch tube perforated for a portion of its length, a mass of refractory porous material in the tube, a sleeve slidable outside of the tube to entirely expose the perforations in one position, and to slide to enclose more or less of the perforated portion, and restrict the flame, said sleeve being slightly larger than the tube to provide a free endwise passage for the air through the sleeve between the tube and sleeve, in all intermediate positions to form a Bunsen burner flame, and spring clips on the sleeve that engage the tube to frictionally hold the sleeve in adjusted positions.
- 10 3. A torch device comprising a fluid container, a closure for the container, a torch

25 tube carried by the closure and perforated at the outer portion of its length, a nozzle extending from the closure into the tube, refractory porous material in the tube surrounding the nozzle, means for controlling the passage of the fluid from the container into the tube, a sleeve slidable outside of the tube to entirely expose the perforations in one position, and to slide to enclose more or 30 less of the perforated portion, and restrict the flame, said sleeve being slightly larger than the tube to provide a free endwise passage for the air through the sleeve between the tube and sleeve, in all intermediate positions to form a Bunsen burner flame, and means to retain the sleeve in various positions of adjustment.

Signed at New York city, N. Y., on October 14, 1926.
